FIG. 1 is a front perspective view of an air vent car mount for electronic devices according to my new design;

FIG. 2 is a bottom perspective view thereof with jaws closed;

FIG. 3 is a front elevational view thereof;

FIG. 4 is one side view thereof; another side view is a mirror image of FIG. 4;

FIG. 5 is a top plan view thereof;

FIG. 6 is a bottom plan view thereof;

FIG. 7 is a section view according to section line 7-7 of FIG. 3;

FIG. 8 is a bottom perspective view with jaws open;

FIG. 9 is an alternate side elevational view with a head tilted in one direction; and,

FIG. 10 is another alternate side elevational view with the head tilted in another direction.

The broken lines shown in the figures are for the purpose of illustrating portions of the air vent car mount for electronic devices and form no part of the claimed design.
